RING SHAPED CLOSURE REMOVER

Raymond H. Williams, Chicago, Ill., assignor to
 White Cap Company, Chicago, Ill., a corpora-
 tion of Delaware

Application June 3, 1950, Serial No. 165,888

4 Claims. (Cl. 215—46)

1

The present invention relates to a new and improved device for removing pressed-on type closure caps from containers.

Closure caps of the pressed-on type are in wide usage in connection with bottles, jars, cans, and the like, in which a wide variety of goods are packaged, especially many different food products. Pressed-on closure caps of the type to which reference is here made are, for example, shown and described in Patent No. 2,339,827 granted January 25, 1944, to William P. White. This cap has an upper top portion having a cylindrical side wall from which depends an outwardly flared skirt portion containing a flexible gasket. The exact details of construction of the pressed-on type caps are not important in so far as the present invention is concerned.

This pressed-on type of cap fits snugly in place over the mouth of a container and therein lies one of its main advantages. However, it is difficult manually to remove one of these caps from its seated position without the use of a tool of some sort, such, for example, as the back side of a knife blade which can be inserted in-between the bottom rim of the cap and the bead formed around the container neck, and then twisted so as to displace the cap.

The object of the present invention, generally stated, is a simple, economical device for removing pressed-on type closure caps of the class described, which device may either be left in place on one of the caps or may be removed and used from time to time as required.

A more specific object of the invention is a cap removing device for removing pressed-on closure caps of the class described wherein the device consists mainly of a ring portion which fits over the top portion of the cap and rests on the outwardly flared skirt portion and has an integral hook formed on one side thereof which extends down, around and under the skirt portion in lifting engagement therewith, this hook portion having an arcuate width within the range of 40 to 50° which gives it maximum contact with the bottom edge of the skirt and yet permits the device to be conveniently and readily applied and removed from the cap while seated on the mouth of a container.

Certain other objects of the invention will, in part, be obvious and will, in part, appear hereinafter.

For a more complete understanding of the nature and scope of the invention, reference may now be had to the following detailed description thereof taken in connection with the accompanying drawings, wherein:

2

Fig. 1 is a side elevational view showing the top of a bottle type container closed with a pressed-on type cap closure to which has been applied a cap lifting or removing device forming one embodiment of the present invention;

Fig. 2 is a view corresponding to Fig. 1 but showing a vertical section of the closure cap and the lifting device taken on line 2—2 of Fig. 1;

Fig. 3 is a view corresponding to Fig. 2 but showing the manner in which the closure cap is lifted off from the mouth of the container or bottle;

Fig. 4 is a top plan view of Fig. 1; and

Fig. 5 is a perspective view looking down on the cap removing or lifting device as shown in Figs. 1-4.

In the drawings, the reference numeral 5 designates a glass bottle container which is intended to be typical and illustrative of jar, bottle and can type containers, generally. A circumferential bead or shelf 6 is formed around the mouth of the bottle below the upper rim or lip 7 thereof. The lip or rim 7 has a diameter which is slightly larger than the portion of the bottle mouth designated at 8 which lies in-between the bead 6 and the rim 7.

In Figs. 1 and 2, the bottle 5 is shown closed by means of a pressed-on type cap 10 which may, for example, be made in accordance with the aforementioned Patent No. 2,339,827. The pressed-on type cap 10 comprises a metal shell which has an upper cylindrical portion 11, the side wall of which is vertical or straight and from the bottom of which integrally depends an outwardly flared skirt portion 12. The bottom circumferential edge of the skirt portion 12 has a rolled under circumferential bead which is indicated at 13 and which serves to grip and retain the bottom edge of a rubber gasket 14.

The cap closure 10 is applied to the mouth of the bottle 5 by pressing it downwardly thereon until the top panel of the cap comes to rest against the top edge of the rim or lip 7 as shown, for example, in Fig. 2. When the container 5 is initially packed by the manufacturer, the closure 10 will ordinarily be applied in vacuo whereby the resulting air pressure acting on the top of the closure 10 serves to supplement the friction action of the gasket in holding it in place. After the closure cap 10 has been once removed, however, it may be reapplied by simply pushing it down in place so that it again seats on the rim 7 and the friction fit or gripping action of the gasket on the container neck will be sufficient to hold the cap firmly in place. In fact, the cap will at all times remain sufficiently tightly on

the container 5 so that it is not conveniently removed without the aid of a tool of some type.

The closure cap 10 or similar type closure caps of the pressed-on, friction fitting type may be easily and conveniently removed by a lifting device which is indicated generally at 15. The lifting device 15 may be formed of any material of sufficient strength such, for example, as metal or plastic.

The lifter 15 is preferably formed in one integral piece and comprises a ring member 16 from the bottom of one side of which projects a hook member 17. The interior of the ring member 16 has a diameter such that it fits snugly down over the upper portion 11 of the closure cap 10 as shown, for example, in Figs. 1, 2 and 3. The hook 17 includes a cap gripping or engaging portion 18 having an arcuate inner edge 20 (Figs. 3 and 4).

The hook 17 also is provided with an outwardly projecting handle portion 21 to the bottom of which pressure may be applied as indicated by the arrow 22 in Fig. 3 in order to lift the closure cap 10 off from its seated position on the mouth of the bottle or container 5.

The hook 17 has an arcuate width within the range of 40 to 50° measured along the circumference of the interior of the ring 16. This width is an important feature, since it permits the engaging portion 18 of the hook 17 to have a maximum engagement with the bottom edge of the closure 10, while at the same time it permits the lifting device 15 to be conveniently and readily applied and removed from the closure cap 10 when it is already in place on a container as shown, for example, in Fig. 1.

It is desirable that the hook 17 have as wide or full engagement with the bottom edge 13 of the closure cap as is permissible since the larger area of contact permits the bearing or lifting pressure to be proportionately reduced, and maintained below a point where either the cap 10 or the lifting device 17 tend to be deformed. Also it permits the lifting device 15 to have a maximum lifting strength for the amount of material and strength of material used in it.

However, the hook 17 cannot have an arcuate width which is too large, otherwise it will not be possible to place the lifting device over the cap 10 and obtain a snug, close fit which prevents accidental slippage of the cap lifter when lifting pressure is exerted thereon.

It will be appreciated that certain changes and modifications may be made in the particular contour and shape of the lifting device 15 including the several portions thereof without departing from the spirit and scope of the invention. Accordingly, all matter described above or shown in the accompanying drawings is intended to be interpreted as illustrative and not in a limiting sense in so far as it concerns details of design which are a matter of choice and subject to variation.

Having fully described a preferred embodiment of the invention, what is claimed as new is:

1. A device for removing from its seated position on the mouth of a container a pressed-on type closure cap having a top portion from which depends an outwardly flared skirt portion, comprising a ring member having an interior diameter substantially the same as the exterior diameter of the cap to be removed and which fits down over the top of said cap and rests on the outwardly flared skirt portion thereof in circumferential engagement therewith and a hook portion formed

integrally with said ring portion and which engages around and underneath said skirt portion whereby said cap may be removed by lifting up on said hook portion.

- 5 2. A device for removing from its seat on the mouth of a container a pressed-on type closure cap having a top portion from which depends an outwardly flared skirt portion, which comprises, a ring member having an interior diameter substantially the same as the exterior of the cap to be removed and which fits down over and around said top portion of the cap and which rests on said outwardly flared depending skirt portion thereof in circumferential engagement therewith, a hook formed integrally on said ring which fits down around and engages said closure cap underneath said skirt portion, and an integral handle portion projecting from said hook whereby lifting force may be applied to said cap to 20 remove it from its seat.
3. A device for removing from its seat on the mouth of a container a pressed-on type closure cap having a top cylindrical portion from which depends an outwardly flared skirt portion having a rolled circumferential bottom edge, which comprises, a ring member the interior of which has a diameter which is substantially the same as the exterior diameter of the cap to be removed and allows the ring to fit snugly over and around said top cylindrical portion of the cap so as to rest on said outwardly flared skirt portion thereof in circumferential engagement therewith, a hook formed integrally on said ring so as to fit down around the skirt portion of said cap, said hook having an inwardly projecting arcuate portion which engages said rolled circumferential bottom edge of said cap when said device is in place thereon, and a handle portion projecting integrally from said hook whereby 40 lifting pressure may be applied thereto, said arcuate portion of said hook having an arcuate width equal to that of a 40 to 50° segment of the circumference of the interior of said ring member and having a radius of curvature approximately equal to that of the interior of said ring.

- 45 4. The combination with a cap for a container, which cap is characterized by a thin sheet metal shell having a substantially cylindrical upper portion and an enlarged lower portion, of a lifter 50 for the cap consisting of a one-piece member having a cylindrical bore of substantially the same height and diameter as the upper portion of the shell, which member fits over the cap in a position substantially flush with the top of the 55 latter and in abutment at the lower end of the bore with the enlarged lower portion of the cap, said member being provided below the lower edge of the cap with an integral inturned portion in engagement with said lower edge and being also 60 provided at a point intermediate the upper and lower edges of the member with an integral outwardly projecting tab portion.
